By Clarence O'Brien
Attorney

UNITED STATES PATENT OFFICE

LEWIS JAMES TOFT, OF TRENTON, NEW JERSEY

AUTOMOBILE HEADLIGHT CONSTRUCTION

Application filed February 28, 1929. Serial No. 343,281.

The present invention appertains to improvements in the art known as illumination, and more particularly the invention has reference to a novel automobile headlight construction.

The principal object of this invention is to provide a headlight construction wherein the beam of light projected by the reflector will be cast upon the roadway in advance of the automobile and in such a manner as to eliminate any glaring rays above the imaginary line of vision for drivers of approaching automobiles.

Another object of the invention is to provide a headlight construction wherein the reflector may be readily adjusted to meet varying conditions.

Another object of the invention is to provide a dimmer for headlights wherein the dimmer may be readily removed for the purpose of repair or replacement.

These and other objects of the invention will become more apparent to the reader after considering the invention as described and claimed hereinafter.

In the drawings:

Figure 1 represents a longitudinal vertical sectional view through the improved headlight construction.

Figure 2 is a front elevation of the improved headlight.

Figure 3 is a top plan view of the upper section of the dimmer.

Figure 4 is a front elevation of the upper dimmer section.

Referring to the drawings wherein like numerals designate like parts, the invention includes a casing 3 open at one end and reduced and inclined upwardly from a point inwardly of said end toward its opposite end 4. The open end portion of the casing 3 is bent backwardly as at 5 and then inwardly to provide a circumferentially extending flange 6. Secured to this flange 6 by suitable set screws 7 is a grooved ring 8 provided with a circumferentially extending flange 9 at its inner edge inclined rearwardly in the manner clearly shown in Figure 1.

A substantially conical shaped reflector 10 with a rear concave portion has its open end

portion cut substantially obliquely and adapted for disposition snugly within the inclined flange 9. Suitable screws 11 are threadedly engaged through the casing 3 for fixedly retaining the reflector in an adjusted position within the casing.

A bushing 12 of suitable insulating material is arranged within an opening in the casing 3 at the reduced end thereof and adapted to support a bulb socket 13 in which a bulb 14 may be secured. The socket 13 is adapted to project through an opening 15 at the reduced end of the reflector 10. The numeral 16 identifies the usual filament of the bulb 14.

Secured to the open end portion of the casing 3 is a rim 17 within which is secured a flanged annulus 18 for holding the lens 19, which lens is adapted to engage the packing strip 20 in the groove of the ring 9 when the rim has been properly secured to the casing by the set screws 21.

Adapted for disposition within the reflector 10 is a dimmer construction which is clearly shown in Figure 2. This dimmer construction includes an upper section 22 and a lower section 23, the upper section consisting of a pair of arcuate members 24-24, each provided with an outwardly projecting flange 25 for disposition between the lens 19 and the ring 8. The upper section also includes a relatively elongated slat 26 disposed at one end between the members 24-24 and adapted to project inwardly of the reflector 10 to terminate very closely to the bulb 14. The slat 26 is inclined rearwardly as are the succeeding slats 27, each succeeding slat being somewhat shorter than its preceding superimposed slats, in the arrangement substantially shown in Figure 1.

The section of the dimmer 23 consists of a pair of arcuate members from each of which projects an outwardly extending flange 28. Between the arcuate members of the lower section are connected a plurality of slats 29 which are inclined rearwardly and are in spaced relation to each other. The slats 26, 27, and 29 are all disposed in a manner so that unobstructed rays may be projected from the bulb 14 directly upon the ground in advance of the headlight and each slat is adapted to

have its upper surface coated with some dull finish so that the rays from the lamp 14 projected thereagainst will not deflect glaringly. It is preferable that the coating be of a blue color which has a somewhat softening effect on a person's eyes. More so than other basic colors.

It is to be understood that certain changes in the specific shape, size, and materials may 10 be resorted to in the construction of this novel headlight without departing from the spirit and scope of the invention as claimed herein-after.

Having thus described the invention, what 15 I claim as new and desire to secure by Letters Patent is:—

A headlight construction comprising a casing open at one end and closed at its opposite end, the closed end of the casing being of 20 concaved shape, the balance of the casing being conical and substantially tangentially disposed with respect to the concave end portion, a reflector of substantially the same shape as the casing and being located within 25 the casing, a light source including a filament arranged within the reflector adjacent the concave end thereof, with the filament in horizontal alinement with the upper edge portion of the open end of the reflector, trans- 30 versely arranged and rearwardly inclined slats within the open end of the reflector and having an upper group thereof in radial disposition with respect to the filament, said group of slats having its uppermost slat ter- 35 minating at its inner end in close proximity to the light source.

In testimony whereof I affix my signature.
LEWIS JAMES TOFT.
